CABLE STRAP

Raymond F. Piasecki, Hazlet, N.J., assignor to The Thomas & Betts Co., Incorporated, Elizabeth, N.J., a corporation of New Jersey

Filed Aug. 12, 1963, Ser. No. 76,194

Term of patent 14 years

(Cl. D54—1)

Fig. 1

Fig. 2

The broken lines in FIGURE 1 are disclosed for illustrative purposes only.

I claim:

The ornamental design for a cable strap, as shown and described.
